Primary Examiner — Keli L Hill*Assistant Examiner* — Harold E Blackwell, II(74) *Attorney, Agent, or Firm* — Finnegan, Henderson, Farabow, Garrett & Dunner, LLP(57) **CLAIM**

The ornamental design for a gauge needle, as shown and described.

DESCRIPTION

FIG. 1 is a front, left, top perspective view of a gauge needle showing our new design;

FIG. 2 is a front, right, bottom perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front elevation view thereof with a display screen and gauge, wherein the display screen and gauge form no part of the claimed design.

The broken lines shown in the drawings depict portions of the display screen and gauge that form no part of the claimed design.
